UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

PUMP FOR SUCTION FEED SYSTEMS.

Application filed August 24, 1922. Serial No. 583,951.

To all whom it may concern:

Be it known that I, LEONARD H. WHEELER, a citizen of the United States, residing in the city of Chicago, in the county of Cook and 5 State of Illinois, have invented certain new and useful Improvements in Pumps for Suction Feed Systems, of which the following is a specification, reference being had to the accompanying drawings, forming a part 10 thereof.

This invention relates to vacuum fuel feed systems for internal combustion engines and its purpose is to provide a suction pump adapted for direct mechanical connection with a moving part of the engine so as to be actuated thereby. It consists of 15 certain features and elements of construction hereinafter described and shown in the drawings as indicated by the claims.

20 In the drawings:

Figure 1 is a diagrammatic side elevation of an engine and fuel feed system including a pump embodying this invention.

Figure 2 is a side elevation of the pump 25 actuating means and a vertical sectional view of the pump itself.

Figure 3 is a transverse section taken as indicated at line 3—3 on Figure 2.

Figure 4 is a transverse section taken as 30 indicated at line 4—4 on Figure 2.

Figure 5 is a top plan view of the pump shown in Figure 2, the valve rods which 35 actuate it appearing in section.

Figure 6 is a side elevation of actuating 40 means combined with a vertical sectional view of a modified form of pumping device.

Figure 7 is a transverse section taken as indicated at line 7—7 on Figure 6.

Figure 8 is a transverse section taken as 45 indicated at line 8—8 on Figure 6.

Figure 1 illustrates conventionally an internal combustion engine, 1, provided with a carburetor, 2, which is fed through a pipe, 3, leading from the vacuum tank, 4, which 50 may be of the usual well understood construction. Said vacuum tank is designed to elevate liquid fuel from the main supply tank, 5, through a pipe, 6, and is operated by suction acting through a suction pipe, 7, connected into the top of the tank, 4. A common arrangement is to tap the suction pipe, 7, into the intake manifold, 8, and rely upon the suction of the intake manifold for actuating the feed mechanism in the tank, 4.

55 The present invention provides a mechani-

cally driven pump, 9, arranged to be actuated by the motion of two adjacent reciprocating valve rods, 10 and 11, of the engine, 1. Preferably the pump, 9, is positioned within the space in which the valve rods, 10 and 11, are enclosed behind a removable cover plate, 12, so that it shall be kept lubricated by the spray or vapor of oil which is usually present in this space.

As shown in Figure 2 the pump consists of a cylinder casting, 9, having an inlet passage, 13, and an exhaust passage, 14, controlled respectively by valves, 15 and 16. The motion of the valve, 16, is checked by a threaded plug, 17, perforated at 18 for discharge of air from the pump. The valve, 15, may be limited as to its play in the fitting, 19, by means of the cross pin, 20, therein and said fitting is threaded at 21, for connection to the suction pipe, 7, as by means of an elbow, 22.

Within the cylindrical bore of the casting, 9, a piston, 23, is mounted for reciprocation and its surface is formed with a plurality of grooves, 24, to receive and distribute oil for keeping the piston well lubricated, and also sealed substantially air tight. Outside the cylinder, 9, the end of the piston is bifurcated at 25 and journals a plug, 26, whose transverse bore fits snugly but slidably upon the rounded end, 27, of a rocker arm, 28, fulcrumed to swing through a limited arc about the axis of a rock shaft, 29, upon whose squared portion, 30, the arm, 28, is fastened by means of a nut, 31. The rock shaft, 29, is journaled in a bearing lug, 32, upstanding from the base of a bracket, 33, whose downwardly offset end, 34, is secured to a ledge, 35, of the engine frame or block by a screw or bolt, 36.

The rocker arm, 28, extends upwardly from the shaft, 29, at one side of the bearing lug, 32, and at the other side there is rigidly secured to the shaft a walking beam, 37, whose opposite ends engage the downwardly extending lugs, 38, of notched fittings, 39, which are secured over the valve tappets, 40, by being clamped under the adjusting nuts, 41, of the valve rods. Preferably each of the fittings, 39, is counterbored at 42 to fit over the tappet, 40, and its open notch, 43, embraces the lower end of the valve rod, as indicated in Figure 5. The location of the pumping device is so chosen that the valve rods, 10 and 11, with which it

is associated are those whose upward movements alternate with each other thus rocking the walking beam, 37, and the rocker arm, 28, for reciprocating the piston, 23, 5 in its cylinder. The cylinder is rigidly supported upon a post, 44, reduced and threaded at its lower end to receive a nut, 45, which clamps it firmly to the base of the bracket, 33, and reduced and threaded at its upper 10 end to engage a threaded hole, 46, in the cylinder casting, 9, in which it is finally locked by a cross pin or rivet, 47.

It will be understood that this extremely simple mechanism will operate automatically whenever the engine is running and without adding any considerable load to the valve tappets, 40, will produce suction through the pipe, 7, which will be more than adequate at all times for operating the vacuum feed apparatus. As is well understood, the vacuum tank, 4, includes internal mechanism, not shown, for venting its suction chamber to the atmosphere to permit discharge of its accumulated contents to the carbureter, 2, through the pipe 3, and during the discharge intervals the pump, 9, will simply run idle.

Figures 6, 7 and 8 show a slightly modified form of pump in which the piston, 50, is 30 sealed by means of a piston ring or packing, 51, and reciprocates in a cylinder, 52, which is closed at both ends, the piston rod, 53, emerging through a central opening in one cylinder head, 54, for operative connection 35 with the rocker arm, 55. Said rocker arm is actuated by the valve tappets, 40, provided with fittings, 39, having lugs, 38, similar to those already described, and engaging the ends of a walking beam, 37, on the rock shaft, 40 56, which differs from the rock shaft, 29, only in certain dimensions. Said shaft is journaled in a bearing, 57, mounted on the bracket, 58, which also supports the pump cylinder casting, 59, through the medium of a U-shaped bracket, 60.

The piston rod, 53, is provided at its outer end with flanges, 61 and 62, the latter being secured by means of a cross pin, 63, through its hub, 64; the rocker arm, 55, is bifurcated 50 at its upper end and carries anti-friction rollers, 65, which engage between the flanges, 61 and 62, at opposite sides of the rod, 53, for transmitting motion from the arm, 55, to the piston rod and its piston, 50. At 55 the upper side of the cylinder, 52, discharge ports, 66, are positioned adjacent each end of the cylinder and are controlled by ball check valves, 67, caged in the counterbores of the ports, 66, by screw plugs, 68, which 60 are perforated at 69 for discharge of air.

At the lower side of the cylinder casing inlet

ports, 70, are formed at each end and register with valve chambers, 71, in an applied fitting, 72, which contains suction or inlet passages, 73, controlled by ball check valves, 74. Said fitting 72, includes a nipple, 75, for attachment of any suitable coupling to connect the suction pipe, 7, which leads from the vacuum tank, 4. As shown in Figure 8, the fitting, 72, is formed with ears or flanges, 76, to receive attaching screws, 77, by which it is clamped to the valve under surface of the cylinder casting preferably with a sheet of impervious packing material, 78, interposed as shown.

The modified form of pump is thus adapted to withdraw air or vapor from the vacuum tank, 4, upon reciprocation of its piston, 50, in either direction and this double acting form of pump may be found more suitable than the single acting form of Figure 2 when the available stroke provided by the motion of the valve tappets, 40, is quite short.

I claim:—

1. In combination with an internal combustion engine a fuel feeding device consisting of a vacuum producing pump of the reciprocating piston type, the same being mounted upon the engine fixed structure and comprising for actuating the pump piston a rocker fulcrumed at its lower end and having its upper end operatively connected with the pump piston; opposite lever arms extending from the lower end of the rocker transversely to its fulcrum axis into the vicinity of two oppositely reciprocating valve rods respectively; and tappets mounted on the valve rods for encounter with the opposite ends of the lever arms respectively. 100

2. In combination with an internal combustion engine a fuel feeding device consisting of a vacuum producing pump of the reciprocating piston type, the same being mounted upon the engine fixed structure and comprising for actuating the pump piston a rocker fulcrumed at its lower end and having its upper end operatively connected with the pump piston; opposite lever arms extending from the lower end of the rocker transversely to its fulcrum axis into the vicinity of two oppositely reciprocating valve rods respectively; and tappets mounted on the valve rods for encounter with the opposite ends of the lever arms respectively, the tappets being formed with forked stems for entering astride the valve rods respectively between a shoulder and a nut thereon. 110

In testimony whereof, I have hereunto set my hand at Chicago, Illinois, this 19th day of August, 1922.

LEONARD H. WHEELER.
